UNITED STATES PATENT OFFICE.

PETER J. MEAD, OF MILWAUKEE, WISCONSIN.

HORSESHOE-PAD.

SPECIFICATION forming part of Letters Patent No. 650,334, dated May 22, 1900.

Application filed August 21, 1899. Serial No. 727,868. (No model.)

To all whom it may concern:

Be it known that I, PETER J. MEAD, of Milwaukee, in the county of Milwaukee and State of Wisconsin, have invented a new and useful Improvement in Horseshoe-Pads, of which the following is a description, reference being had to the accompanying drawings, which are a part of this specification.

My invention has relation to improvements in horseshoe-pads.

One object of the invention is to provide an improved form of horseshoe-pad of such construction that all jarring is effectually prevented by reason of the fact that the pad presents a yielding surface which will prevent lameness, the invention also comprehending as a feature of construction a bearing of the pad directly against the frog of the hoof, whereby danger of lameness is reduced to a minimum.

The invention furthermore comprehends as an object the peculiar arrangement, disposition, and construction of the pad, whereby the hoof, at the rear contracted portion thereof, is adapted to be expanded, and corns, sores, or other affections of the hoof thereby prevented.

A further object contemplated is the provision of an improved construction whereby slipping of the horse on rough or slippery pavements is prevented, especially when the projecting points from the shoe become worn and thereby unserviceable for the purpose of preventing slipping.

With the above primary and other incidental objects in view the invention consists of devices and parts or their equivalents, as hereinafter more fully set forth.

In the accompanying drawings, Figure 1 is an inverted view of a shoe attached to a hoof, showing my improvements properly applied. Fig. 2 is a side view of Fig. 1. Fig. 3 is a section on the line 3 3 of Fig. 1. Fig. 4 is a plan view of a modified form of construction. Fig. 5 is an edge view of Fig. 4. Fig. 6 is a view of a plain thin rubber pad adapted for covering the entire shoe for the purpose of preventing snow or other accumulations from getting into the hoof. Fig. 7 is an edge view of Fig. 6. Fig. 8 is a sectional detail view

showing the pad attached by means of a rivet instead of by a screw-bolt.

Referring to the drawings, the numeral 9 indicates a horse's hoof, and 10 the usual frog formation on the under side of the hoof and 55 at the rear thereof.

The numeral 11 indicates an ordinary form of horseshoe, provided at the front end with the usual elongated sharpened prong 11' and at its rear end with downwardly-extending 60 points 12 12, also adapted to prevent slipping. The shoe is secured to the hoof by the usual nails provided for that purpose, but these nails are not driven entirely around the shoe to the rear extremities thereof, but the rear 65 portions of the shoe are left unsecured, as most clearly shown in Fig. 1.

In Figs. 1, 2, and 3 I show a rear pad 13, which extends across at the rear and from one side of the shoe to the other, and on its 70 upper side at opposite ends are cut-out portions, (indicated by the numerals 14 14,) forming recesses, which permit said pad to fit beneath the rear portions of the shoe, and thereby leave the portion of the pad intermediate of 75 the rear ends of the shoe free to project upwardly and bear on the under side of the frog 10. The rear edge of pad 13 is also cut out at opposite ends, as indicated by the numerals 15 15, in order to accommodate the downwardly-extending prongs 12 12. The front edge of the pad 13 is provided at an intermediate point thereof with a forwardly-projecting tongue 16, which is shaped to conform to and bear against the frog, preferably against 85 substantially one-half the length of said frog. The pad 13 is preferably secured by means of screw-bolts 17, which pass through said pad and engage the rear portions of the shoe. If desired, however, the pad may be 90 secured by means of rivets. This means of securing is illustrated in Fig. 8, wherein a rivet (designated by the numeral 18) is shown as passing through the pad and also through the shoe. The pad is preferably formed with 95 a roughened under surface, as clearly shown in Fig. 1, whereby a firmer and more secure footing is given to the animal and danger of slipping thereby lessened.

From the construction described it will be 100

seen that I provide a pad which is applied to the under side of the shoe at the rear thereof and that this pad forms a firm bearing against the frog, and as the rear portions of the shoe to 5 which the pad is applied are, as previously stated, left unsecured to the hoof the said hoof, at its rear contracted portion, is free to expand laterally slightly, owing to the upward pressure of the pad against the frog of 10 the hoof, whereby lameness, corns, sores, or other affections of the hoof are prevented. The pad provides a firm and yielding bearing for the horse on the ground, and should the animal be affected with a splint all jar 15 against the affected bone is prevented. The yielding action afforded by the pad also prevents slipping, and should the prongs 12 become so worn as to be unserviceable for that purpose the rear portion of the pad is then 20 free to bear directly against the ground, and thereby take the place of the prongs to prevent the animal slipping on icy, wet, or smooth pavements. Another point of advantage of my pad is the fact that when it becomes worn 25 it can be readily removed from the shoe and a new pad substituted therefor.

In Figs. 1 and 2 I show at the front of the shoe a transversely-arranged pad 19, which is also preferably roughened on its under side 30 and is arranged to the rear of the prong 11' and is secured at its ends at opposite sides of the front of the shoe by means of screw-bolts, rivets, or the like. When the front prong 11' becomes so worn down as to be unfit to 35 further act to prevent slipping, this pad will then come in contact with the ground and serve to perform that function.

In Figs. 4 and 5 of the drawings I show a modified form of construction, wherein the 40 rear pad, corresponding to the pad 13 of Figs. 1, 2, and 3, (but indicated in said Figs. 4 and 5 by the numeral 20,) has extending from its front edge a thin covering-sheet 21, which extends over the entire shoe from side to side 45 and to the front extremity thereof. This pad 20 is shown as unprovided with the forwardly-projecting tongue 16. (Shown in Fig. 1.) The thin covering 21 acts as a guard to prevent snow, mud, or other substances from getting 50 into the hollow of the hoof. Should snow or other substances come in contact with this covering, said covering will be forced upwardly and will then subsequently spring downwardly, and thereby expel or throw the 55 snow or other substances off. This thin covering is preferably formed as an integral part of pad 20, although, if preferred, it may be separate therefrom and extend from the front edge of the pad forwardly.

In Figs. 6 and 7 I show a form of construction 60 wherein the pad consists merely of a thin covering extending entirely over the shoe from front to rear and across from side to side, the portion 20 of the Figs. 4 and 5 construction being omitted. This thin covering 65 (indicated by the numeral 22) acts not only as

an antislapping pad, but also as a guard, the same as the thin covering 21, Figs. 4 and 5, to prevent snow or other accumulations from getting into the hollow of the hoof, said 70 snow or accumulations being expelled or forced off the cover by the resilient or springy character of said covering.

In the Figs. 4, 5, 6, and 7 forms of construction the hollow of the hoof above the coverings may be packed with ocher, cotton-battting, or some similar material. In all the forms of construction the pads and covering are preferably made of rubber. I do not wish to be understood, however, as limiting myself to this particular material, as any other desirable material, such as leather and the like, could be substituted without departing from the spirit and scope of my invention.

While I have only shown the pad of the 85 Figs. 1 to 3 form of construction as provided with a roughened under surface, yet it will be understood that, if desired, the under surfaces of the pads of the other forms of construction may be similarly roughened, or this 90 roughening may be omitted altogether, if desired.

What I claim is—

1. In a horseshoe-pad, the combination, 95 with a horseshoe, of a pad secured to and arranged against the under sides of the ends of the shoe at the heel of the shoe, but not projecting rearwardly beyond said ends of the shoe, and extending across from side to side of the heel of the shoe, the portion of 100 the pad in the space between the rear ends of the shoe extending upwardly a sufficient distance to bear against the frog of the hoof.

2. In a horseshoe-pad, the combination, 105 with a horseshoe, of a pad secured to and arranged against the under sides of the ends of the shoe at the heel of the shoe, but not projecting rearwardly beyond the ends of the shoe, and extending across from side to side of the shoe, the top surface of said pad at opposite ends being cut out to form recesses to receive the rear ends of the shoe, whereby the portion of the pad in the space between the rear ends of the shoe is adapted to extend upwardly a sufficient distance to bear against 115 the frog of the hoof.

3. In a horseshoe-pad, the combination, 120 with a horseshoe provided at its rear ends with downwardly-projecting prongs, of a pad secured to and arranged against the under 125 sides of the ends of the shoe at the heel of the shoe, but not projecting rearwardly beyond said ends of the shoe, and extending across from side to side of the shoe, the portion of the pad in the space between the rear ends of the shoe extending upwardly a sufficient distance to bear against the frog of the hoof, and the side edges of the pad being cut out to accommodate the downwardly-extending prongs.

4. The combination, with a horseshoe, of 130 a pad secured to and arranged against the

under sides of the ends of the shoe at the heel of the shoe, but not projecting rearwardly beyond said ends of the shoe, and extending across from side to side of the heel

5 of the shoe, the portion of the pad in the space between the rear ends of the shoe extending upwardly a sufficient distance to bear against the frog of the hoof, and a pad arranged against and secured to the under side

of the shoe at the front thereof and extending 10 across from side to side of the shoe.

In testimony whereof I affix my signature in presence of two witnesses.

PETER J. MEAD.
